REINFORCED CONCRETE FLOOR CON-
STRUCTUREWilliam N. Murch, University City, Mo., assignor
to Sinclair Construction Company, University
City, Mo., a corporation of Missouri

Application March 26, 1936, Serial No. 70,922

5 Claims. (Cl. 72—66)

My invention relates to reinforced concrete floors. Its principal object is to devise a reinforced concrete floor construction which can be made without using centering or temporary supports. Another object is to devise a reinforced concrete floor construction that will be light and strong and economical of labor and material. The invention consists in the arrangements and combinations of parts hereinafter described and 10 claimed.

In the accompanying drawings, which form part of this specification and wherein like reference numerals refer to like parts wherever they occur, 15 Fig. 1 is a top plan view of the metal trusses, hollow tile and spacing members of a hollow floor construction embodying my invention,

Fig. 2 is a side elevation looking in the direction of the arrows 2—2 in Fig. 1,

Fig. 3 is a sectional view on the line 3—3 in Fig. 1,

Fig. 4 is a sectional view on the line 4—4 in Fig. 1,

Fig. 5 is a sectional view on the line 5—5 in Fig. 4,

Fig. 6 is an elevation of a portion of one of the spacer members,

Fig. 7 is a sectional view at one of the metal truss members of Fig. 3 showing the poured concrete in place,

Fig. 8 is a sectional view similar to Fig. 4, showing the poured concrete,

Fig. 9 is a sectional view showing the invention as applied to a metal beam or girder,

Fig. 10 is a sectional view of a modification in which the metal trusses have their upper chords resting on the tops of metal I-beams,

Fig. 11 is a partial sectional view similar to Fig. 7, showing a nailing strip for a wood floor applied to the upper chord of the metal truss, and

Fig. 12 is a sectional view showing a modified form of tile.

According to the present invention, a series of 45 metal trusses 1 are supported at their ends on walls 2 or girders. A truss suitable for the present construction consists of an I-beam slotted and expanded so as to spread apart the top flange 3 and bottom flange 4 and still leave them integral- 50 ly connected by tie members 5. Such expanded beams or girders are well known structural elements.

The trusses are strong and rigid enough to support, without deflection, their own weight plus 55 the weight of the hollow tiles 6, and wet concrete

7 hereinafter mentioned. The lower chords of the trusses are wider than the lattice portion thereof and their margins form ledges on which the ends of hollow tiles 6 are supported. The lower chords are wide enough to leave the proper space 5 for pouring concrete ribs above them and between the ends of the tiles supported on opposite sides thereof.

In a typical construction, the trusses are arranged parallel with each other and are spaced 10 apart by means of suitable spacing members 8 such as are shown for example, in Fig. 6. The spacing members there shown have recesses 9 in the underside adapted to receive the lower chords of the trusses and thereby enable the 15 main stretches of such spacing members to be positioned with the upper surfaces of their marginal portions substantially flush with the upper surfaces of the marginal portions of the lower chords of the trusses. Preferably, the spacing 20 members are formed with upstanding flanges 10 for the purpose of stiffening them, said flanges being located inwardly from the sides thereof, leaving the marginal portions to constitute ledges 25 for supporting the sides of the tiles 6. By this 30 arrangement, the spacing members function as struts or distance pieces to keep adjacent trusses spread apart, as tie members to keep said trusses from spreading too far part, and as supporting members for the adjacent tiles.

In the construction illustrated, the hollow tiles 6 are supported on the lower chords of the trusses, the individual tile being of such length as to reach from truss to truss but short enough to leave ample spaces between its end wall and the 35 end wall of the tile supported on the opposite margins of the truss for the formation of a reinforced concrete beam 11. Those tiles that are next to the spacing members have one edge resting on the ledges thereof, the tiles on opposite 40 sides of the spacing member being arranged sufficiently far enough apart to provide for the formation of a concrete rib 12 extending from truss to truss.

Preferably the hollow tiles are of less depth than 45 the distance between the upper and lower chords of the trusses. The spaces between ends of the tiles on opposite sides of the trusses and the spaces above the spacing members are filled with concrete which is extended upwardly far enough 50 to embed the upper chords of the trusses and cover the tops of the tiles in a continuous slab. In the operation of pouring the concrete, the lower chords of the trusses and the spacing members function as the bottoms of the form-work for 55

the beams or ribs, and the vertical sides of the tiles function as the side members of the form-work for such beams or ribs, while the tops of the tiles function as the form-work for the portion 5 of the slab above said tiles.

In Fig. 12 is shown a modified form of tile which has an angular recess 30 extending along the lower edge of one side wall, a recess 31 near the bottom of the outer side wall and a projecting lower lip forming the lower wall of said recess. The angular recess 30 permits one edge portion of said tile to rest on the lower chord of the truss and the chord of the truss at the other side of said tile is received in the recess 31, the lip 10
